Filed Nov. 13, 1968, Ser. No. 14,432

Term of patent 14 years

Int. Cl. D23—04
U.S. Cl. D23—151

FIGURE 1 is a front elevational view showing my new design;

FIGURE 2 is a rear elevational view thereof;

FIGURE 3 is a side elevational view thereof; and

FIGURE 4 is a fragmentary enlarged cross-sectional view taken on the line 4—4 of FIGURE 1.

The dominant features of the design reside in those parts shown in full lines.

I claim:

The ornamental design for a housing for a wall mounted ventilator fan, substantially as shown and described.
